WEIGHING SCALE

Berend Bernard Schierbeek, Leidschendam, Netherlands,
assignor to Maatschappij Van Berkel's Patent N.V.,
Rotterdam, Netherlands, a limited-liability company of
the Netherlands

Filed Feb. 24, 1965, Ser. No. 83,967

Term of patent 14 years

(Cl. D52—10)

FIG. 1

FIG. 2

FIG. 1 is a front perspective view of a weighing scale embodying my new design; and

FIG. 2 is a rear perspective view of the weighing scale shown in FIG. 1.

The undisclosed side of the weighing scale is substantially the same in appearance as the side shown, except for the knob.

I claim:

The ornamental design for a weighing scale, substantially as shown and described.
